UNITED STATES PATENT OFFICE.

ALONZO E. RHOADES, OF HOPEDALE, MASSACHUSETTS, ASSIGNOR, BY MESNE ASSIGNMENTS, TO DRAPER CORPORATION, OF PORTLAND, MAINE, A CORPORATION OF MAINE.

AUTOMATIC WEFT-REPLENISHING LOOM.

1,212,399.

Specification of Letters Patent. Patented Jan. 16, 1917.

Application filed October 5, 1915. Serial No. 54,203.

To all whom it may concern:

Be it known that I, ALONZO E. RHOADES, a resident of Hopedale, in the county of Worcester and State of Massachusetts, have 5 invented certain new and useful Improvements in Automatic Weft-Replenishing Looms, of which the following is a specification.

In automatic weft replenishing looms 10 wherein the replenishment is effected by ejecting a spent weft carrier from the shuttle and inserting a full weft carrier in the shuttle (as in the well-known Northrop or Draper loom, as exemplified, for example, in 15 United States Letters Patent of Northrop No. 529,940, November 27, 1894) it is important that no transfer of weft carriers should be made except when the shuttle is 20 in the proper position in the shuttle box at the weft replenishing side of the loom. If the shuttle is not in the proper position when the transfer of weft carriers takes place breakage is apt to occur.

The object of the present invention is to 25 insure the shuttle being in the correct position in the shuttle box at the replenishing side of the loom when the transfer of weft carriers takes place. If the shuttle is not in the correct position, mechanism is provided 30 which prevents the action of the transferrer so that no transfer of weft carriers takes place and consequently no breakage can occur.

The preferred embodiment of the present 35 invention is illustrated in the accompanying drawings wherein—

Figure 1, is a plan view of the shuttle box at the replenishing side of the loom. Fig. 2, is a front view of the said shuttle box. 40 Fig. 3, is a vertical section through said shuttle box illustrating also so much of the transferrer and the magazine for filled bobbins as is necessary for an understanding of the present invention. Fig. 4, is an end view 45 of the said shuttle box.

Referring to the drawings, A, is the lay; B, is the shuttle box at the replenishing side of the loom; C, is the shuttle; D, is a weft carrier in the shuttle; E, is a portion of the 50 rotary magazine containing filled weft car-

riers F; G, is the swinging transferrer; H, is the transferrer dog pivoted on the lower arm of the transferrer and I, is the bunter on the lay which coöperates with the transferrer dog H. All of these parts are similar to those shown in the aforesaid Northrop Patent No. 529,940. During the normal running of the loom the transferrer G, occupies its elevated position shown in Fig. 3, ready to co-act with the spare weft carrier F, beneath it. The transferrer dog H, during the normal running of the loom occupies the position shown in full lines in Fig. 3, where it is beyond the reach of the bunter I, when the lay swings forward. When replenishment 55 is required, the exhaustion or approaching exhaustion of the working weft is detected by one of the detectors such as are commonly employed in this class of looms, and the transferrer dog H, is swung upwardly so 60 that its notched end J, is brought into the path of the bunter I, on the lay. Hence, when the lay swings forwardly the bunter encounters the dog H, and swings it to the position illustrated in the dotted lines 65 shown in Fig. 3. This is accompanied by a downward swing of the transferrer G, which inserts a filled weft carrier in the shuttle C, and ejects the spent or nearly spent weft carrier D. This is the customary 70 action of the Northrop loom and has long been well known.

The drawings also illustrate the usual 75 picker K, and picker stick L, at the replenishing side of the loom.

When the shuttle has entered the shuttle box at the replenishing side of the loom it may not occupy the correct position, and the illustrated mechanism is such that in that event the transferrer dog H, will not be operatively encountered by the bunter I, and the transferrer G, will not act.

As shown in Fig. 1, a horizontal lever M, is pivoted at a, to the shuttle box at the replenishing side of the loom and it extends 95 forwardly outside of the picker K. The lever M, at its middle is provided with an abutment N, which is directly in the path of the outer end of the picker K. At its front end the lever M, is pivoted at b, to a 100

rod O, which extends horizontally along the front of the shuttle box as shown in Fig. 1. This rod O, at its inner end has a deflector P, which is located just above the plane of the bunter I. The deflector P, has a slot c, through which passes a screw stud Q, which screws into the top of the bunter I. As shown in Fig. 3, the front face d, of the deflector P, is downwardly and rearwardly inclined. The bunter I, is provided with a downwardly extending projection R, which likewise has its front face e, downwardly and rearwardly inclined. The bunter proper I, also has, as shown, a downwardly and rearwardly inclined face f. As shown in Fig. 3, the inclined faces d, e, and f, are all in the same plane.

Fig. 1, shows the shuttle at its proper position in the shuttle box to receive a fresh weft carrier. As here shown its outer end bears against the picker K, and the picker in turn bears against the abutment N, on the lever M. As a consequence the deflector P, occupies its extreme outer position with the inner end of the slot c, against the shank of the screw stud Q. The shuttle cannot be driven outwardly any farther than is shown in Fig. 1, because the stud Q, prevents any further outward movement of the shuttle. When the deflector P, occupies the position shown in Fig. 1, the bunter I, is fully exposed opposite the transferrer dog J, and, consequently, when the transferrer dog is lifted as the result of the detection of exhaustion or approaching exhaustion of the working weft, the bunter I, encounters the elevated transferrer dog and the transfer is effected.

When the shuttle is driven out of the shuttle box at the replenishing side of the loom a spring S, swings the lever M, inwardly until the outer end of the slot c, encounters the shank of the screw stud Q. The deflector P, then covers the bunter I.

Should the shuttle, on arriving at the shuttle box at the replenishing side of the loom when a transfer should take place, not enter the box far enough to swing the lever M, outwardly, the deflector P, will be left in a position covering the bunter I, and with its inclined face d, in register with the uplifted transferrer dog H. Consequently, when the lay swings forward, the inclined face d, of the deflector encounters the transferrer dog and, as the result, the transferrer dog is swung downwardly, turning on its pivot g, instead of the transferrer G, being swung on its pivot h. During this downward swing of the transferrer dog H, on its pivot g, it rides down the inclined faces d, f, and e, to the position shown in full lines in Fig. 3. The customary spring connections between the transferrer dog H, and its actuating mechanism permit this downward swing. Consequently, the trans-

fer cannot take place until the deflector P, is entirely removed from the path of the transferrer dog H. It is obvious that the deflector P, must be moved outwardly far enough to be out of reach of any portion 70 of the rear face of the transferrer dog H, before the transferrer dog can be operatively engaged by the bunter I. The organization of the deflector P, and its actuating devices is preferably such that the bunter I, cannot operatively engage the transferrer dog H, unless the deflector P, is moved to its extreme outer position with the inner end of its slot c, against the shank of the screw stud Q, as illustrated 75 80 in Fig. 1. This insures the exact proper position of the shuttle in the shuttle box for the reception of the incoming weft carrier. The shuttle cannot move outwardly any farther because the deflector P, is at its 85 extreme outer position. Any failure of the shuttle to reach this extreme outer position results in the deflector P, obstructing the transferrer dog H, and preventing its operative connection with the bunter I. 90

I claim—

1. A weft replenishing loom having, in combination, a transferrer, a transferrer dog pivoted thereto, a lay, a bunter on the lay having a rearwardly and downwardly inclined front face and coöperating with said transferrer dog, a projection extending downwardly from the bunter having a downwardly and rearwardly inclined front face, a picker, a picker stick, a slotted deflector sliding above the bunter and having a downwardly and rearwardly inclined front face in the same plane as the downwardly and rearwardly inclined faces of the bunter and the bunter projections, a lever outside 105 of the picker having an abutment against which the picker is moved by the shuttle entering the shuttle box at the replenishing side of the loom, a spring moving said lever toward the picker, a rod connecting the front end of said lever with said deflector, and a stud secured to said bunter and extending through the slot in said deflector. 110

2. A weft replenishing loom having, in combination, a transferrer, a transferrer dog, a lay, a bunter on the lay coöperating with said transferrer dog, a movable deflector alongside the bunter, a lever on the lay at the replenishing side of the loom coöperating with the picker to be moved thereby when the shuttle enters the neighboring shuttle box, a rod connecting said lever with said deflector whereby said deflector is moved away from the bunter when the shuttle is correctly located in the shuttle box, 125 and means for limiting the movement of the deflector in both directions.

3. A weft replenishing loom having, in combination, a transferrer, a transferrer dog, movable means located on the lay to 130

control the action of the dog, and means governed by the position of the shuttle in the shuttle box at the replenishing side of the loom coöperating with said transfer con-
5 trolling means so as to render said dog in- operative when the shuttle is improperly

located in the shuttle box and to render said transferrer operative when the shuttle is properly located in the shuttle box.

In witness whereof, I have hereunto signed my name.

ALONZO E. RHOADES.
